UNITED STATES PATENT OFFICE

CHARLES A. PRATTE, OF DENVER, COLORADO

VACUUM SANDER

Application filed May 9, 1930. Serial No. 450,983.

This invention relates to improvements in vacuum air sanders of the type described and claimed in United States Letters Patent No. 953,228, granted to me on March 29, 1910.

5 In the operation of railway locomotives, as well as electric street cars and other vehicles that run on steel rails, it is often necessary to sand the track in order to obtain the necessary friction for pulling the load, and 10 for this purpose locomotives are provided with a sand box located at the top of the boiler. This sand box is connected with pipes that run down adjacent the drive wheels to a point close to the rails and when it is necessary to sand the rails, the engineer opens a 15 valve that releases air into the pipes and this in turn conveys sand through the pipes and onto the rails.

20 In the patent above identified, I have shown and described a sander that is provided with nozzles that correspond to the nozzles of ordinary injectors and these nozzles are connected with the compressed air system in such a way that when air is supplied to the 25 nozzle, sand will be conveyed from the sand box and blown into the space in front of the driving wheel and the rail on which it is resting.

30 It has been found from experience that sanders of the type to which this invention relates are liable to become clogged, due to the fact that the sand will pack when it is not used for some time, and also due to the further fact that during operation moisture enters the sander and this causes the sand to adhere to such an extent that it interferes somewhat with the operation.

35 It is the object of this invention to produce an improved sanding device of the type described in the above identified patent, which shall be provided with means for stirring the sand, so as to loosen the same, if it should become clogged, and which shall also be so constructed that the air will enter through one 45 of the sanding pipes and therefore be taken from such a position that it will be quite free from moisture.

40 In order to describe this invention so that it can be readily understood, reference will be had to the accompanying drawing in which

the preferred embodiment thereof has been illustrated, and in which:

Fig. 1 is a view showing one side of a locomotive and showing my improved sanding device in place thereon; and

Fig. 2 is a view partly in section and partly in elevation showing my improved sander.

55 In the drawing reference numeral 1 designates the boiler of a locomotive and 2 the drive wheels, while 3 designates the sand box that is located on the top of the boiler. In this embodiment only a single sand box has been illustrated, but with very large locomotives it is quite frequently necessary to employ two sand boxes. A pipe 4 connects with the sand box near the bottom thereof and extends downwardly. Secured to the lower end of this pipe is my improved vacuum sanding device which has been indicated as a 60 whole by reference numeral 5. A stop cock 6 is usually located in the pipe 4, so that it can be closed if the sander is removed for repair. My improved sander is preferably formed from cast metal such as cast-iron or 65 brass and is provided with a central recess or cavity 7. Extending upwardly from the central portion of the sander is an inwardly threaded hub 8 with which the lower end of pipe 4 is connected. Extending outwardly 70 from opposite sides are tubular projections 9 that are internally threaded for the reception of the connectors 10. Partitions 11 extend downwardly from the top of the sander on each side of the opening in hub 8. The 75 lower edges of partitions 11 terminate substantially at the level of the lower surface of the openings in tubular members 9. The lower end of the recess terminates in a 80 threaded opening 12 that is closed by means of a plug 13. This plug can be removed for 85 cleaning the interior of the sander whenever this is necessary. A U-shaped pipe 14 has its ends connected to the interior of the sander on opposite sides of the partitions 11 in the 90 manner shown in Fig. 2. Secured to the outer ends of the connectors 10 are T's 15. These T's have the upwardly extending openings 16 provided with threads and connected 95 with these threaded openings are nozzles 17. The lower ends of the nozzles extend down- 100

wardly to a point substantially at the level of the lower surface of the opening in connectors 10. The upper ends of the nozzles terminate in threaded plugs 18, which have their upper ends tapered as indicated by reference numeral 19. Secured to these plugs are sleeves 20 that form part of a pipe union and whose upper ends have their outer surfaces threaded for the reception of the coupling members 21. The air pipes 22 are provided at their ends with flanges 25 that are engaged by the couplings 21 in the manner shown in Fig. 2. When air under pressure is admitted through pipes 22, it will flow through the openings in the nozzle and emerge from the latter at a high velocity and this emerging air sets up a suction which reduces the pressure within the sander, thereby causing air to flow into that side of the sander through the pipe 14. The air that enters through pipe 14 carries with it sand from the recess 7 and this sand then enters the opening 24 and is driven through the pipe 25 and against the periphery of the drive 25 wheel, thereby depositing it in the space between the drive wheel and the rail in the manner shown in Fig. 1. Plug 13 is provided with an opening through which a rod 26 extends. The inner end of this rod is provided with a hook 27 and the outer end with a ring 28 that serves as a handle. The engineer, by grasping the handle 28 and moving and rotating the rod can stir the sand so as to break up any clogging of the latter. It will be noted that pipe 14 connects the interior of the sanding device on opposite sides of partition 11 and that when air is admitted through one of the nozzles so as to set up a suction in the manner described, air will enter that part of the sander after it has passed through the pipe 14. The air that passes through pipe 14 will be drawn upwardly through one of the sand pipes 25 and as this pipe terminates a short distance above the rail and near the drive wheel, the air is usually dry and therefore very little moisture is introduced into the sander by the air when the sander is operating. The air pipes 22 extend to a point within the cab and are each provided with a valve or stop cock 29 by means of which the engineer controls the flow of the air. In the embodiment illustrated, only one side of the locomotive has been shown, but the other side is also provided with a sander located in a corresponding position and both of these sanders are connected with the air pipes 22. The sander can be located close to the sand box as shown in the drawing, or it may be located underneath the running board 30, if this should be found desirable. In the latter case, the pipe 4 may run between the boiler and the boiler sheathing so as to be out of sight.

From the above description it will be seen that I have produced a sander that is pro-

vided with means for stirring the sand so as to break up any clogging whenever this occurs and which is also so constructed that the air that enters the same is taken through the sand pipes from a point near the surface of the rail and in this manner the air is quite free from moisture even when the weather is damp or rainy.

Having thus described my invention, what I claim as new is:

1. A sander provided with a centrally located depending sand trap through which the sand is delivered to the sander, lateral extensions, air nozzles for removing the sand from the trap on the ejector principle, and arranged to discharge across the outer extremities of said extensions and means for stirring the sand.

2. A sander provided with a centrally located chamber, arranged by means of a depending trap, to prevent the escape of the sand by gravity, extensions connected with the chamber and leading outwardly therefrom in opposite directions, air nozzles mounted on the said extensions and arranged to discharge air across the outward extremities of the extensions, conduits connected with the sander for delivering sand to the track and means for stirring the sand in the trap.

3. A sander comprising a depending sand trap, ejectors located adjacent to the trap for removing the sand therefrom, extensions between the trap and the ejectors, conduits connected with the sander and arranged to carry the sand to the track under the influence of the air pressure from the ejectors and mechanical means for stirring the sand.

4. A sander comprising a trapped casing having lateral outlets, air nozzles extending transversely of said outlets and at the outer extremities thereof, the casing having an opening communicating with the atmosphere in the vicinity of the trap, means for passing air through the nozzles under pressure across the outer extremities of the outlets, the nozzles being so located that a strong air current is induced outwardly from the trap from the said aperture to the nozzles, whereby the sand is carried into the path of the air issuing from the latter, substantially as described and mechanical means for stirring the sand.

5. A sander comprising a centrally located sand containing trap, and having lateral extensions leading outwardly from the trap, an air nozzle arranged to discharge air transversely across the outer extremity of each extension, the sander being provided with apertures located close to the trap, the apertures on opposite sides being connected by a pipe whereby outwardly directed air currents are induced by the vacuum resulting from a discharge of the air from the nozzles, substantially as described.

6. A sander comprising a casing having a

centrally located chamber formed in the lower part thereof, the casing having lateral extensions leading outwardly from its upper portion, the casing having a depending flange located directly above the chamber whereby the sand is trapped in the chamber, openings located adjacent to the said flange and in communication with the interiors of the lateral extensions, the openings being also in communication with each other, and air nozzles arranged to deliver air across the outer extremities of the lateral casing extensions whereby air currents are induced from said air currents outwardly for the purpose of removing sand from the trap and carrying it into the path of the air issuing from the nozzles, substantially as described.

In testimony whereof I affix my signature.
CHARLES A. PRATTE.
